UNITED STATES PATENT OFFICE.

OTTO H. HARTMANN, OF CASSEL-WILHELMSHOHE, GERMANY, ASSIGNOR TO
SCHMIDT'SCHE HEISSDAMPF-GESELLSCHAFT M. B. H., OF CASSEL-WIL-
HELMSHOHE, GERMANY, A CORPORATION OF GERMANY.

LOCOMOTIVE BOILER.

Application filed September 12, 1924, Serial No. 737,312, and in Germany October 1, 1923.

My present invention relates to locomotive boilers and particularly to boilers of the type employing a fire box provided with water tubes, a longitudinal boiler having smoke tubes, and a superheater located within these smoke tubes or some of them. The purpose of this invention is to arrange or operate a locomotive engine in such a manner that, without any substantial change in the type of construction employed hitherto, it will be possible to generate steam of higher pressure than customary heretofore. I am aware that various attempts have been made to so construct locomotive engines as to enable high pressure steam to be produced in them. It has also been proposed to substitute for the ordinary fire box a water tube fire box of the Brotan type, and to combine a longitudinal boiler having smoke flues with superheaters arranged within such flues. All these experimental attempts, however, have resulted in failure, which was due chiefly to the fact that boiler scale was deposited in the water tubes of the fire box to such an extent as to soon prevent satisfactory operation. The deposit of scale was so heavy that, for instance, the tubes or rings at the bottom of the fire box became totally obstructed, so that the supply of water to the water tubes was interrupted and these tubes burned out.

The drawbacks mentioned above are avoided according to my present invention by combining with a locomotive boiler, which may be a longitudinal boiler of the usual type having smoke flues and a smoke flue superheater, a water tube fire box which, however, is not in direct contact with the steam or water space of the longitudinal boiler as has been customary hitherto. The steam, or mixture of steam and water, generated in the water tubes of the fire box, according to this invention, is employed for the indirect heating of the water in the longitudinal boiler and is carried through a continuous circulation path through said boiler and back to the fire box. With this arrangement, purified water can be used in the water tubes of the fire box, thus preventing the formation and deposit of boiler scale. A suitable way of constructing the locomotive boiler in this case involves the arrangement of tubular coils above the smoke tubes and within the longitudinal

boiler, the admission ends of these coils being connected with the upper portion of the water tubes of the fire box, while the outlets of said coils are connected directly with the lower portion or base ring of the fire box or they may be connected with a feed water heater through which the water produced by condensation of the heating steam passes before entering the said base ring. Preferably the water tubes of the fire box and the tubular coils within the longitudinal boiler are subdivided into several units or elements, each of which can be thrown into and out of action by itself, thereby providing a plurality of separate circulating paths for the steam or mixture of steam and water. I am aware that it is not novel, per se, to subdivide into several units the heating coils provided in connection with a system for the indirect heating of boilers.

Several examples of my invention have been illustrated in the accompanying drawings, in which Fig. 1 represents diagrammatically a longitudinal section of a locomotive engine having a boiler arranged according to my invention. Figs. 2 and 3 are vertical sections taken on the lines 2-2 and 3-3 respectively of Fig. 1. Fig. 3^a is a diagrammatic view showing another form of my invention in side elevation, and Fig. 3^b is a cross-section on line 3^b-3^b of Fig. 3. Fig. 4 is a longitudinal section similar to Fig. 1 but illustrating another embodiment of my invention, and Figs. 5 and 6 are transverse sections on the lines 5-5 and 6-6 respectively of Fig. 4.

The locomotive boiler shown in Figs. 1, 2, and 3, comprises a water tube fire box 1 and a longitudinal boiler 2, having fire tubes or smoke tubes. The fire box is shown as comprising a base ring 3 and upright water tubes 4, forming the side walls and the top wall of the fire box and communicating at the top with a longitudinal collector tube 5. At 6, I have indicated a bridge wall which may be supported in part by means of two water tubes 7 suitably bent, as will be understood from Figs. 1 and 2. From the collector tube 5, the steam produced within the tube system 3, 4, 5, 7, is conveyed through conduits 8 to the heating elements contained in the boiler 2, and located above the smoke tubes or fire tubes 9 thereof, in which superheating elements may be arranged in the

usual or any approved manner. The heating elements receiving the steam from the collector tube 5 may consist of coils 10 receiving the supply of steam from the conduits 8 by way of a header or headers 11, the other ends of said coils being connected with similar headers 12, see Fig. 3. It will be understood that the steam coming from the fire box through the conduits 8 first reaches the collectors or headers 11, then passes through the heating coils 10 to the headers 12 and from the latter returns to the base ring 3 of the fire box by way of conduits 13. A closed circulation path is thus provided. The steam produced in the fire box therefore is utilized as a heating medium for the water within the longitudinal boiler. The medium circulating within the coils 10 will be either steam or a mixture of steam and water. This steam or this mixture gives off heat through the walls of the tubes 10, to the water within the boiler and the wafer formed by the condensation of steam within the tubular coils 10 returns to the base ring 3, it being noted that the heating coils 10 are at a level considerably above said base ring. Since the path through which the steam or mixture referred to circulates is closed, there is no need of replenishing the supply of water contained therein and therefore purified water may be employed without any material increase of expense. By the use of purified water, I am enabled to overcome entirely the danger of formation of boiler scale or of corrosion of the tubes by substances contained in impure water. In order to avoid leaks, it is desirable to construct the fire box of units made of forged or welded parts.

When it is desired to subdivide the circulation path of the heating medium into a plurality of units, this may be done in various ways. For instance (as indicated in Figs. 1 and 3), the heating coils 10 located on one side of the central longitudinal plane of the boiler may receive steam from the connection 14 of the collector tube 5, while the heating coils 10 located on the other side of said plane may receive steam from the connection 15 of said collector. When this arrangement is adopted, the entire fire box would be constructed in two parts, that is, the base ring as well as the collector tube 5 would consist of two portions having no communication with each other, and these two sections of base ring and of collector tube 5 would have their separate sets of water tubes 4 to connect them and one section would supply steam through the outlet connection 14, while the other would supply steam through the outlet connection 15. Similarly, the return connections from the heating coils 10 on opposite sides of the longitudinal central plane of the locomotive would, in this case, lead to different sections

of the base ring 3. In other words, there would be two complete circulating paths, each entirely separate from the other. An arrangement of this character is illustrated by Figs. 3^a and 3^b. 3 and 3^a are the two base ring sections and 5 and 5^a are the corresponding collector tube sections. 8 and 8^a are the pipes leading from the respective sections to the heating coils 10 and 10^a respectively. It will be obvious that the number of sections into which the base ring and the other portions of the circulating path are subdivided may be increased. The advantage of having more than one circulating path is greater security of operation. If, for instance, one of the several circulating paths should leak or become damaged, it can be thrown out of action temporarily while the other circulating path or paths would still enable the locomotive to operate sufficiently either to complete its trip or at least to reach the repair shop.

In the example of my invention illustrated by Figs. 4, 5, and 6, the headers 12' are located in the smoke box of the locomotive and the pipes 13', which receive the water condensed within the heating elements 10, do not lead directly to the base ring 3, but first to one path of a heat exchange apparatus 16 through the other path of which circulates a medium to be heated, for instance, feed water. After having thus given off its heat to the feed water or other substance to be heated, the condensation product returns to the base ring 3 through the pipe or conduits 13, as indicated in Fig. 4. It will be obvious that in this second form of my invention as well, the circulation path of the heating steam may be subdivided into two or more sections, each independent of the others and that various other modifications may be made without departing from the nature of my invention as set forth in the claims.

I claim:

1. A locomotive boiler plant comprising a longitudinal boiler having smoke tubes and steam superheating means in said tubes, a water tube fire box, and connections for the indirect heating of the water in said boiler by means of the steam produced in the water tubes of the fire box.

2. A locomotive boiler plant comprising a boiler proper, a water tube fire box, and connections, extending from the water tubes of said fire box to the water space of the boiler, for the indirect heating of the water in said boiler by means of the steam produced in said water tubes.

3. A locomotive boiler plant comprising a boiler proper, a water tube fire box, and connections, extending from the water tubes of said fire box to the water space of the boiler, for the indirect heating of the water in said boiler by means of the steam pro-

duced in said water tubes, said connections forming a continuous closed path, so as to return to the water tubes, any water resulting from the condensation of steam in said path.

4. A locomotive boiler plant comprising a longitudinal boiler proper, a water tube fire box, a heating device located in that portion of the boiler proper which contains water under normal operating conditions, said device having an internal path closed to the interior of said boiler, and connections from said water tube fire box to the interior path of said heating device and back from said interior path to said water tube fire box, to form with the water tubes of the fire box an entirely closed system, said system comprising a space for holding water to be converted into steam and also comprising a space, including the internal path of said heating device, for containing the steam generated from the water contained in said system.

5. A locomotive boiler plant comprising a boiler proper, a water tube fire box, and connections, extending from the water tubes of said fire box to the water space of the boiler, for the indirect heating of the water in said boiler by means of the steam produced in said water tubes, said connections forming a continuous closed path, so as to return to the water tubes, any water resulting from the condensation of steam in said path, the water tube fire box being subdivided into a plurality of sections having individual connections to form a like number of separate closed paths for the circulation of the steam generated in said water tubes, and for the return of any water resulting from the condensation of such steam.

49 6. A locomotive boiler plant comprising a boiler proper, a water tube fire box, and connections, extending from the water tubes of said fire box to the water space of the boiler, for the indirect heating of the water in said boiler by means of the steam produced in said water tubes, said connections forming a continuous closed path, so as to return to the water tubes, any water resulting from the condensation of steam in said path, and a feed water heater included in the return connection from the boiler to the water tube fire box.

7. A locomotive boiler plant comprising a boiler proper and a water tube fire box the steam collecting space of which is separate

from the steam and water space of the boiler proper, in such a manner that a generation of steam in the fire box is feasible at a temperature and a pressure higher than those of the steam generated in the boiler proper. 60

8. A boiler plant comprising a water tube fire box constituting a steam generator having a steam collecting space, and a boiler having a steam and water space out of connection with the first mentioned space, so 65 that the steam produced in said generator may be of a temperature and pressure different from those of the steam produced in said boiler.

9. A locomotive boiler plant comprising a 70 boiler proper, a fire box formed by water tubes, a tubular heating device located within the water space of the boiler proper at a level above the water tubes of the fire box, the interior of said tubular heating device 75 being out of communication with the boiler proper, and connections for leading to said heating device the steam produced in the water tubes of the fire box and for returning to said water tubes any water resulting from 80 the condensation of the steam in said heating device.

10. A locomotive boiler plant comprising a boiler proper, a fire box formed by water tubes, a tubular heating device located within the water space of the boiler proper, the interior of said tubular heating device being out of communication with the boiler proper, and connections for leading to said heating device the steam produced in the water tubes 85 of the fire box and for returning to said water tubes any water resulting from 90 the condensation of the steam in said heating device.

11. The method of generating steam for 95 locomotives which consists in heating water in tubes at the fire box of the locomotive, causing the steam generated from such water to pass out of contact with, but in heat exchange relation to, a body of water in the 100 locomotive boiler so as to convert the water in said boiler into steam by the heat of such steam generated in the fire box, and returning to the fire box tubes the water resulting from the condensation of the steam which 105 has heated the water in the locomotive boiler.

In testimony whereof I have hereunto set my hand.

OTTO H. HARTMANN.
